MAGNETIC TAPE UNIT

Franciscus M. Michiels, Antwerp, Belgium, assignor to
International Standard Electric Corporation, New York,
N.Y., a corporation of Delaware

Filed Jan. 22, 1964, Ser. No. 78,315

Term of patent 14 years

(Cl. D26—5)

The figure is a front perspective view of a magnetic tape unit showing my new design.

The side of the machine not shown is substantially a mirror image of the side shown, while the top and rear of the machine, not shown, are substantially plain and unornamented.

I claim:

The ornamental design for a magnetic tape unit, as shown and described.
